CLAIM

The ornamental design for a swimming pool cleaner part, as
shown and described.

DESCRIPTION

FIG. 1 is a first perspective view of a swimming pool cleaner
part, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a first perspective view of a second state of the
swimming pool cleaner part; and,

FIG. 10 is a second perspective view of the second state
thereof.

The broken lines shown in the drawings depict portions of
the swimming pool cleaner part that form no part of the
claimed design.

1 Claim, 10 Drawing Sheets
